(57) **CLAIM**

The ornamental design for a speaker component retainer bridge, as shown and described.

DESCRIPTION

FIG. 1 is a perspective view of a speaker component retainer bridge;

FIG. 2 is a top plan view thereof;

FIG. 3 is a bottom plan view thereof;

FIG. 4 is a right side elevation view thereof; and,

FIG. 5 is a front elevation view thereof.

Broken lines are used to illustrate portions of the speaker component retainer bridge that form no part of the claimed design.
